UNITED STATES PATENT OFFICE

1,997,617

TRIMMING ATTACHMENT FOR SEWING MACHINES

Albert H. Weis, Nyack, N. Y., assignor to Metropolitan Sewing Machine Corporation, Nyack, N. Y., a corporation of Delaware

Application February 5, 1934, Serial No. 709,741

29 Claims. (CL 112—124)

This invention relates to a detachable trimming attachment for sewing machines which may be applied to any well-known make of machine, it being illustrated, however, as applied to a well-known lock stitch machine in which the stitch is made with a needle and a bobbin thread or with a plurality of needles and a bobbin thread.

The object of this invention is the provision of an improved trimming attachment for producing a pinned edge adjacent the seam whereby the stitched article may have its edges pinned to prevent raveling of the threads of the trimmed edge, and which trimming attachment is so mounted that it can be quickly attached to or detached from the machine to permit the machine to be used for plain stitching, the primary object of the invention being to provide a simple, readily attachable and inexpensive trimming mechanism employing a rotary cutter and improved driving means effective to operate the cutter at high speed under varying adjustments of the cutter and, at the same time, avoid the use of a lower roll or roller co-operating with the cutter.

A further object of the invention is the provision of improved positive acting means for regulating the pressure of the cutter on the work thereby eliminating the use of springs, and which means includes means for automatically preventing too much pressure being applied to the cutter and the consequent damage thereto.

In the manufacture of dresses and similar articles, it is sometimes required that an operator do the entire work of making a garment, sewing the pieces together, stitching on the trim, such as lace, binding, piping, cording and other stitching such as sewing in pleats, tucks or folds frequently required by the unlimited variations in designs and styles of the respective factories where such machines are used. To meet this requirement, it is essential that the feeding and trimming member be detachable from the machine quickly and without difficulty.

In addition to this ready detachability, I have provided an improved trimming mechanism having a rotary cutter and so constructed that it can be operated from the needle bar at high speed and in which the stroke of the driving mechanism for the cutter can be varied so that the movement of the cutter will coincide with the feed stroke of the feeding mechanism according to the desired length of stitch and in which the cutter may be shifted toward and from the needle for making narrow or wide seams and also positioned with its axis ahead of or in the rear of the needle whereby, as the cutter acts as a feed, certain

advantages are obtained on some classes of work.

In the present improvement I have eliminated the necessity of providing a lower roll or roller co-operating with the rotary trimmer and, consequently, have made it practicable to set the cutter slightly in advance or in the rear of the needle and when set with its axis intersecting the plane of the needle it will not interfere with its use to trim curved or irregular surfaces and, therefore, it is not confined to straight-away stitching.

In the drawing accompanying and forming a part of this specification, Fig. 1 is an end elevation of so much of a well-known Wilcox and Gibbs sewing machine as it is necessary to illustrate herein, and with this improved trimming attachment applied thereto.

Fig. 2 is a top view of the trimming attachment.

Fig. 3 is a detail view of the adjustable driving connection to the cutter shaft.

Fig. 4 is a detail view of the throat plate and its hardened insert or plate.

Fig. 5 is a partly sectional view of the same parts with the cutter in position, and

Fig. 6 is a view of the positively acting pressure regulating means for the cutter.

Similar characters of reference indicate corresponding parts in the several views.

Before explaining in detail the present improvement and mode of operation thereof, I desire to have it understood that the invention is not limited to the details of construction and arrangement of parts illustrated in the accompanying drawing since the invention is capable of other embodiments, and that the phraseology which I employ is for the purpose of description and not of limitation.

The sewing machine illustrated has the usual bed 1, trunk 2 and top arm 3 for the upper shaft 4 which is mounted in bearings and operates in the usual way. A hand and belt wheel is located at the rear end and at the front end the machine has a rotary take-up 5 for the needle thread. The head of the machine carries the usual presser bar 6 and presser foot 7. The needle 8 coacts with a rotary hook and bobbin 9 to make the well-known lock stitch. The needle is carried by the needle bar 10 having a chuck 11 for clamping the needle. A stud screw 12 carried by the chuck operates in the forked end 13 of a lever 14 secured at 15 to a rock shaft 16 supported for rocking movement in a tubular shaft 17.

This tubular shaft carries a swingable bracket 18 and this bracket is supported by bearings 20 and 21 on the shaft 17. The trimmer supporting

- bracket 22, through a part of which extending between the bearings 20 and 21 the tubular shaft also passes and is secured thereto at 18, is secured to the bed of the machine by a clamping bolt 23 which may be provided with either hex head or a wing nut 24 for quick removal from the machine or reattaching it to the machine and by providing an elongated slot 23' for the bolt 23, the trimmer supporting bracket 22 and its cutter may be adjusted back and forth relative to the needle. The needle bar operated rock shaft 16 has secured to its opposite end 25, a lever arm 26. This lever arm has an elongated slot 27 in the free end thereof for the reception of an adjustable stud 28, see Figs. 2 and 3, projecting into a slot 29 of a lever 30, being clamped in position by a wing nut 31. By shifting the stud, the throw of the levers 26 and 30 may be varied to correspond with the feed and length of stitch desired.
- 20 The lever 30 carries clutching members (not shown) that operate in the housing 31' of the clutch 32 secured to the trimmer shaft 33 operating in bearings 34 and 35 carried at the front end of the swinging bracket 19.
- 25 Between the bearings 34 and 35 is an adjusting collar 36 secured to the trimmer shaft 33. By loosening this collar and the clutch 32, the shaft may be shifted endwise in the bearings to make wide or narrow seams.
- 30 The left hand end of the shaft 33 is provided with a flange 37 against which is fixed in a suitable manner a pinking or design rotary cutter 38 operating close to the line of stitching to sever the goods with a zig-zag or other design edge.
- 35 This cutter 38 is brought into cutting relation with the top surface 39 of a hardened steel insert or anvil 40 provided with dove-tailed edges 41 to fit into a dove-tailed recess 42 of a throat plate 43. The dove-tailed recess extends part way through the thickness of the metal of the throat plate. The throat plate is seated in a milled recess of the bed plate 1 and is rigidly supported, being held in place by screws 44. This throat plate, in working position accommodates a feed dog 45 which operates through the openings 46 to feed the work. The throat plate also has one or more needle holes 47 for free passage of the needle to form the stitches.
- 40 The dove-tailed slot for the hardened insert is made with a round cutter and this provides a stop surface as at 48 to prevent the insert from moving inward against the feed 45. The opposite edge comes flush with the edge 49 of the throat plate where it rests against the casting of the bed of the machine which thus prevents movement of the insert in that direction. While the dove-tailed hardened insert is easily removed after the throat plate is taken off the machine, yet it cannot shift in any direction while in working position on the machine.
- 45 A rotary cutter of suitable design 38 is shown in working position against the hardened insert 40 in Fig. 5.
- 50 A work guide 50, see Fig. 1, is secured to the top of the bed of the machine in advance of the trimmer for conveniently guiding the work and regulating the amount to be trimmed off from the edge thereof.
- 55 To rigidly and positively support the cutter 38 to co-operate with the hardened insert 40, the supporting bracket 22 has an overhanging arm 51, the end of which is provided with an adjusting screw 52, see Fig. 6, threaded into the arm 51 and secured thereto by a set screw 51'. This
- 60 adjusting screw is hollow and is provided with

a vertical plunger or pin 53 loosely mounted to slide up and down in the screw when not fastened thereto. It is of suitable diameter and length to permit the bottom end to rest on top of the bearing 35 carrying the cutter shaft and thus positively holds the cutter 38 in cutting position on the hardened insert 40. The pin 53 is secured to the adjustable hollow screw 52 by a shearable pin or cotter pin 54 and to prevent undue pressure being applied to the cutter 38, a size of cotter pin is selected that will shear when too much pressure is applied to the cutter and thus prevent damage to the rotary cutter 38. By adjusting the screw 52 in the bracket arm 51 the pin is shifted to regulate the pressure on the cutter thereby doing away with the use of springs for this purpose.

In the application of this improvement to any of the well-known sewing machines, it is merely necessary to decide on the exact location of the rotary cutter with respect to the needle and provide holes for the clamping screw 24, and arrange the needle bar operated lever 14 so that its slotted end will engage the screw stud 12. This lever 14 rocks the shaft 16 and gives movement to the lever arms 26 and 30 of the intermittent clutch 31-32 secured to the cutter shaft 33 which thus has a step by step rotary movement imparted thereto in bearings 34 and 35 and so gives a step by step rotary movement to the pinking cutter 38. To change the extent of movement of the cutter to coincide with the feed stroke for giving the desired length of stitch, the stud 28 may be adjusted in the slots of the lever arms 26 and 30 so that the movement of the cutter 38 will advance the work being trimmed equal to the step by step advancement of the four-motion feed 45.

By reason of the fact that in this improvement the cutter co-operates with a hardened plate so that a lower co-operating roll or roller 40 is eliminated, located in proximity to the needle and looper or loop taker, the cutter can be set ahead of or in the rear of the needle and without interfering with its proper work. When located in advance of the needle and given a stroke 45 greater than the stroke of the four-motion feed, it would have a gathering effect to ruffle or shirr the work as it trims in advance of the stitching and when located in the rear of the needle it would operate as a puller feed as it trims the 50 work.

After many practical demonstrations over a considerable period of time, it has been found that this improved trimmer operates highly satisfactorily without a bottom roller and that there 55 is practically no wear on the cutter or on the anvil block or insert. As a result, a number of machines have already been manufactured and marketed and this desirable result, it is believed, is due to the fact that the stationary 60 hardened block or anvil is rigidly supported and the rotary zig-zag cutter is also rigidly supported above it without any spring action so that the rotary cutter can be adjusted to the hardened surface so as to allow no space between the two 65 members. Consequently, anything fed between the members will be severed with the result that the cutter in practical operation is effective to do the work without noticeable wear of the cutting surface and without any appreciable wear 70 of the hardened block or anvil.

The present improvement is shown applied to a sewing machine although obviously it is adapted for use independently thereof. On certain classes of work the needle, hook and bobbin or 75

Looper may be removed and the improvement used for trimming the edges of cloth either before or after being made into garments, that is, before or after they are stitched. Even when 5 used without the stitching mechanism, there is quite an advantage in using the trimmer attached to a sewing machine especially when such a machine has a four-motion feed and presser foot in that, as the improved rotary zig-zag cutter also acts as a feed, better control of the work 10 is obtained and there is less chance of damaging the garments.

It is to be understood that by describing in detail herein any particular form, structure or 15 arrangement, it is not intended to limit the invention beyond the terms of the several claims or the requirements of the prior art.

Having thus explained the nature of my said invention and described a way of constructing 20 and using the same, although without attempting to set forth all of the forms in which it may be made, or all of the modes of its use, I claim:

1. A trimming attachment for sewing machines comprising a rotary trimmer, means for 25 rotating it, a stationary rigidly supported co-operating hardened anvil, and means for rigidly supporting the trimmer in position to co-operate with the anvil.

2. A trimming attachment for sewing machines comprising a rotary trimmer, means for 30 rotating it, a stationary rigidly supported co-operating hardened anvil, means for rigidly supporting the trimmer in position to co-operate with the anvil, and means for positively regulating the pressure of the trimmer.

3. A trimming attachment for sewing machines comprising a rotary trimmer, means for 35 rotating it, a stationary rigidly supported co-operating hardened anvil, means for rigidly supporting the trimmer in position to co-operate with the anvil, and means for positively regulating the pressure of the trimmer and including means for automatically relieving the pressure on the trimmer when the pressure is excessive.

4. A trimming attachment for sewing machines comprising a rotary trimmer, means for 40 rotating it, a stationary rigidly supported co-operating hardened anvil, means for rigidly supporting the trimmer in position to co-operate with the anvil, and adjustable means for positively regulating the pressure on the trimmer and including shearable means for automatically releasing the pressure on the trimmer when the pressure is excessive.

5. A trimming attachment for sewing machines having a throat plate and comprising a rotary trimmer, means for rotating it, a stationary rigidly supported co-operating hardened anvil carried by the throat plate, and means for rigidly 45 supporting the trimmer in position to co-operate with the anvil.

6. A trimming attachment adapted for attachment to the bed of a sewing machine having stitching elements including a needle and comprising a hardened stationary anvil block carried by the bed in proximity to the path of the needle, a rotary cutter co-operating with the anvil and also located in proximity to the needle, and means for rotating the cutter.

7. A trimming attachment adapted for attachment to the bed of a sewing machine having stitching elements including a needle and comprising a hardened stationary anvil block carried by the bed in proximity to the path of the needle, a rotary cutter co-operating with the anvil

and also located in proximity to the needle, means for rotating the cutter, and means for regulating the pressure of the cutter relative to the anvil.

8. A trimming attachment adapted for attachment to the bed of a sewing machine having stitching elements including a needle and comprising a hardened stationary anvil block carried by the bed in proximity to the path of the needle, a rotary cutter co-operating with the anvil and also located in proximity to the needle, means for rotating the cutter, and means for regulating the stroke of the cutter according to the length of the stitch.

9. A trimming attachment adapted for attachment to the bed of a sewing machine having stitching elements including a needle and comprising a hardened stationary anvil block carried by the bed in proximity to the path of the needle, a rotary cutter co-operating with the anvil and also located in proximity to the needle, means for rotating the cutter, and springless means for adjusting and positively regulating the pressure of the cutter relative to the anvil.

10. A trimming attachment adapted for attachment to the bed of a sewing machine having a reciprocating part and a needle and comprising a hardened stationary anvil block carried by the bed in proximity to the path of the needle, a rotary cutter co-operating with the anvil and also located in proximity to the needle, and means connected with the reciprocating part for rotating the cutter.

11. A trimming attachment adapted for attachment to the bed of a sewing machine having stitching element including a needle and comprising a hardened stationary anvil block carried by the bed in proximity to the path of the needle, a rotary cutter co-operating with the anvil and also located in proximity to the needle and adjustable toward and from the needle to vary the width of the trimmed portion, means for rotating the cutter, and means effective to secure the cutter in any of its adjusted positions.

12. A trimming attachment adapted for attachment to the bed of a sewing machine having stitching elements including a needle and comprising a hardened stationary anvil block carried by the bed in proximity to the path of the needle, a rotary cutter co-operating with the anvil and also located in proximity to the needle and adjustable toward the front or rear of the needle, means for rotating the cutter, and means effective to secure the cutter in any of its adjusted positions.

13. A trimming attachment adapted for attachment to the bed of a sewing machine having stitching elements including a needle and comprising a hardened stationary anvil block carried by the bed in proximity to the path of the needle, a rotary cutter co-operating with the anvil and also located in proximity to the needle and adjustable toward and from the needle to vary the width of the trimmed portion and also adjustable toward the front or rear of the needle, means for rotating the cutter, and means for securing the cutter in any of its adjusted positions.

14. A trimming attachment for sewing machines comprising a supporting bracket, a bracket shiftable relative thereto, a rotary cutter carried by said shiftable bracket, means for rotating the cutter, means carried by the supporting bracket for regulating the pressure on the cutter, and stationary rigid means below and co-operating with said cutter.

15. A trimming attachment for sewing machines comprising a supporting bracket, a bracket shiftable relative thereto, a rotary cutter carried by said shiftable bracket, means for rotating the cutter, and means carried by the supporting bracket for regulating the pressure on the cutter and comprising a rotating screw, and a pin carried thereby and fastened to said screw. 5
16. A trimming attachment for sewing machines comprising a supporting bracket, a bracket shiftable relative thereto, a rotary cutter carried by said shiftable bracket, means for rotating the cutter, and means carried by the supporting bracket for regulating the pressure on the cutter and comprising a rotating screw and a pin carried thereby and fastened to said screw by shearable means. 10
17. A trimming attachment for sewing machines comprising a rotary trimmer, means for rotating it, and means for regulating the pressure of the trimmer and comprising a positively acting adjustable means automatically releasable when the pressure is excessive. 15
18. A trimming attachment for sewing machines comprising a rotary trimmer, means for rotating it, and means for regulating the pressure of the trimmer and comprising a positively acting adjustable means automatically releasable when the pressure is excessive and comprising an adjustable threaded member, a pin loose therein, and shearable means connecting the pin and threaded member. 20
19. A trimming attachment for sewing machines having a needle bar and comprising a rotary trimmer located in proximity to the needle at one side thereof, a shaft supporting said trimmer, means connected with the needle bar, a rock shaft connected to said means, and means connecting said rock shaft and trimmer shaft for rotating the trimmer shaft. 25
20. A trimming attachment for sewing machines having a needle bar and comprising a rotary trimmer located in proximity to the needle at one side thereof, a shaft supporting said trimmer, means connected with the needle bar, a rock shaft connected to said means, and means connecting said rock shaft and trimmer shaft for rotating the trimmer shaft step by step. 30
21. A trimming attachment for sewing machines having a needle bar and comprising a rotary trimmer located in proximity to the needle at one side thereof, a shaft supporting said trimmer, means connected with the needle bar, a rock shaft connected to said means, and adjustable means connecting said rock shaft and trimmer shaft for rotating the trimmer shaft. 35
22. A trimming attachment for sewing machines having a needle bar and comprising a rotary trimmer located in proximity to the needle at one side thereof, a stationary rigidly supported hardened anvil located in proximity to the needle, means for rigidly supporting the trimmer in position to co-operate with the anvil, a rotary shaft supporting said trimmer, means connected with the needle bar, a rock shaft connected to said means, and means connecting said rock shaft and trimmer shaft for rotating the trimmer shaft. 40
23. A trimming attachment for sewing machines having a needle bar and comprising a rotary trimmer located in proximity to the needle at one side thereof, a stationary rigidly supported hardened anvil located in proximity to the needle, means for rigidly supporting the trimmer in position to co-operate with the anvil, a rotary shaft supporting said trimmer, means connected with the needle bar, a rock shaft connected to said means, and means connecting said rock shaft and trimmer shaft for rotating the trimmer shaft. 45
24. A trimming attachment for sewing machines having a needle bar and comprising a supporting bracket, a bracket swingable relative thereto, a rotary trimmer located in proximity to the needle at one side thereof, a shaft supporting it and carried by the swingable bracket, means connected with the needle bar, a rock shaft connected with said means and supported by the supporting bracket, means connecting said rock shaft and trimmer shaft for rotating the latter, a stationary rigidly supported hardened anvil located in proximity to the needle and co-operating with said trimmer, and means for regulating the pressure on the trimmer. 50
25. A trimming attachment for sewing machines having a needle bar and comprising a supporting bracket, a swinging bracket, a pair of parallelly located shafts, one carried by the swinging bracket and the other extending through both of said brackets, a rotary cutter carried by the shaft of the swinging bracket, means for rotating said cutter shaft from the other shaft, and means connected with the needle bar for actuating the shaft extending through both of said brackets. 55
26. In a sewing machine having a presser foot and a four-motion feed, a rotary trimmer constructed to operate as a feed in co-operation with the four-motion feed, means for rotating it, and means for adjusting the trimmer in line with the feeding operation of the four-motion feed to the front or rear of the needle. 60
27. In a sewing machine having a bed having a stationary hardened surface, a presser foot and a four-motion feed, a rotary trimmer co-operating with the hardened surface, means for operating it, and means for adjusting the trimmer in line with the feed to the front or rear of the needle. 65
28. A trimming attachment adapted for use with a sewing machine having stitching mechanism including a needle bar and comprising a rotary trimmer, means for operating it, a stationary hardened surface co-operating with the trimmer, and means for adjusting the trimmer back and forth toward the rear or front of the needle bar. 70
29. A trimming attachment adapted for use with a sewing machine having stitching mechanism including a needle bar and comprising a rotary trimmer, means for operating it, a stationary hardened surface co-operating with the trimmer, means for adjusting the trimmer back and forth toward the rear or front of the needle bar, and means for adjusting the trimmer transversely to said first adjustment. 75
